UNITED STATES PATENT OFFICE

2,457,609

PITCH CHANGING MECHANISM

George James Smith-Pert and Archibald Graham Forsyth, Cheam, England, assignors to The Fairey Aviation Company Limited, Hayes, England

Application February 8, 1945, Serial No. 576,740

6 Claims. (Cl. 170—160.32)

1

This invention relates to variable pitch propellers.

In light weight, two bladed propellers, it is desirable to provide a simple, light weight, reliable arrangement for changing the pitch of the blades between fine and coarse pitch. It is a principal object of the invention to provide such an arrangement.

Light weight two bladed propellers are frequently provided with counterbalance weights. These are sometimes in the form of segment shaped plates disposed in parallel planes at the bases of the blade sockets and tangential to the propeller drive shaft. In accordance with the present invention, such counterbalance weights are employed as a part of the pitch changing arrangement in such a manner as to effect a long moment arm for the turning movement. It is an important object of the invention to accomplish such results.

The invention employs movement of the counterbalance weights to effect a pitch changing movement from, say, fine to coarse, and employs a piston actuated by oil under pressure, either from the engine lubricating system or from a separate source, for moving the counterbalance weights in the opposite direction and consequently for returning the propeller blades to fine pitch position.

These and other objects of the invention will become more apparent from the following description and claims and accompanying drawings, in which:

Fig. 1 is a longitudinal vertical section (with some parts in elevation) of one embodiment of the invention;

Fig. 2 is a front elevation of the same;

Fig. 3 is a top plan view with one detail being shown in section;

Fig. 4 is a side elevation, partly in section, of one of the elements of the pitch changing mechanism;

Fig. 5 is a front end view of the same element;

Fig. 6 is a front end view of another embodiment;

Fig. 7 is a longitudinal vertical section (with some parts in elevation) of the modification illustrated in Fig. 6; and

Fig. 8 is a front end view of further modification.

In Fig. 1 the tubular propeller drive shaft 10 is shown as extending forwardly from the engine 11. Threadedly mounted on the drive shaft 10 as at 12 is a sleeve member 13 forming part of the oil pressure means which will be later described.

The propeller hub 14 is disposed on the propeller drive shaft 10 forwardly of the sleeve 13. The hub 14 is secured in the usual manner by the rings 15 and 16. The forward ring 16 is provided with a flange 17 having an annular inwardly pro-

2

jecting portion 18 which is disposed in an annular groove 19 in the tubular member 20. The tubular member 20 is threadedly secured on the front end of the propeller drive shaft 10. One or more pins 21 extend outwardly through holes 22 in the propeller drive shaft 10 and through slots 23 in the tubular member 20 to lock the member 20 with respect to the drive shaft 10. The tubular member 20 has a circular flange 24 provided with a series of holes 25 near its outer circumference.

The propeller hub 14 is formed with tubular castings 26 which, through the sleeves 27, support the tubular sockets 28. Base members 29 to which the blade roots are secured by means of long screws, are mounted for rotary movement within the sockets 28.

The propeller hub structure 14, 26, carries two counterbalance weights 31 and 32, each of which is comprised of a fairly thick plate generally of segment shape in plan. The plates are integral with or secured to rings 33 which extend respectively about the tubular castings 26.

As shown in Figs. 1 and 3, the counterbalance weights 31, 32 are secured to the base members 29 by means of bolts 34 which extend through slots 35 in the tubular castings 26 and thence into the base members 29.

From Fig. 3 it will be noted that each plate of the counterbalance weights 31, 32 is provided with a cutout 36 to provide easy access to the bolts 34. Also, the peripheral edges of the plates are provided with a notch 37. These notches 37 are engaged by the arms 38 (Fig. 2) which extend radially from a tubular sleeve element 39. It will be noted from Fig. 1 that the sleeve element 39 is disposed concentrically within the tubular member 20. It is, however, mounted for relative rotary movement with respect to the latter.

Secured at the front end of the unit is a cap member 40 having an inwardly extending tubular spring receiving portion 41. The cap member 40 is secured by means of nuts 42 which engage bolts 43 extending from the spacer ring 44. The spacer ring 44 has lateral lugs 45 and bolts 46 pass through slots 47 therein and through the holes 25 in the flange 24 of the tubular member 20 to which the bolts are secured.

Mounted for axial sliding movement within the hollow propeller drive shaft 10 is a piston having a head 48 and a forwardly extending tubular body 49. The forward end of the body is adapted to move within the annular space formed between the concentrically separated sleeve member 39 and the tubular spring receiving portion 41 of the cap member 40.

As shown in Figs. 4 and 5, the forward end of the piston body 49 is enlarged and is provided on its outer surface with a number of spiral grooves 50. The inner surface of the sleeve member 39 is

provided with complementary ribs 51 (Fig. 1) which engage in the grooves 50.

The inner surface of the front end of the piston body 49 is formed with grooves 52 disposed parallel to the axis of the body (Figs. 4 and 5) and these grooves 52 are engaged by complementary ribs 53 (Fig. 1) on the outer surface of the tubular spring receiving portion 41 of the cap member 40.

A coil spring 54 bears at one end against the head 48 of the piston and at its other end is disposed in the spring receiving portion 41 and bears against the cap member 40. From Fig. 2 it will be seen that the flange 24 of the tubular member 20 is provided with forwardly extending lugs 55, 56. These lugs are threaded to receive stop bolts 57, 58. Lock nuts 59, 60 are provided. The stop bolts 57, 58 are employed to limit the movement of the arm 38.

Means is provided for introducing oil under pressure to the interior of the hollow propeller drive shaft 10. Reference has already been made to the sleeve 13 forming a part of such means. This sleeve 13, as indicated, is threadedly mounted on the drive shaft 10 to rotate therewith. The sleeve 13 is formed with an inner annular groove 61 which communicates with a hole 62 in the drive shaft 10. The sleeve 13 is also provided with an outer annular groove 63 and an oblique passage 64 connects the grooves 61 and 63.

Mounted on the sleeve 13 in surrounding relation thereto is a ring member 65 which, however, is separated from the sleeve by a stationary tubular member 66 having an outward flange at its forward end.

The ring member 65 is stationary with respect to the engine and provided with an inlet oil passage 67 adapted to be connected with a source of oil under pressure (not shown). Also connecting with this passage is an annular groove 68 formed in the ring member 65. The tubular member 66 has an opening 69 which connects the groove 68 of the ring member and the groove 63 of the sleeve 13.

The arrangement operates in the following manner.

The pitch of the propeller blades upon starting is in fine pitch position. After the climb the speed of rotation of the propeller hub will increase and the centrifugal force resulting will cause the counterbalance weights 31, 32 to move toward the plane of rotation of the blades. Since the counterbalance weights are secured to the blade roots, such movement of the counterbalance weights will consequently change the pitch of the blades to coarse pitch position. Since the arms 38 are engaged in the notches 37 in the counterbalance weights movement of the weights will move the arms 38 and also the sleeve member 39 of which they are a part. The amount of movement of the counterbalance weights and consequently of the pitch changing movement is limited, however, by the stop bolt 57 which, as is apparent, may be adjusted.

When it becomes necessary to return the blades to fine pitch position, irrespective of the amount of centrifugal force, such pitch changing movement is effected by introducing oil under pressure into the passage 67 in the ring member 65. This oil enters groove 68, passes through the opening 69 into groove 63 of the sleeve 13 and then through the oblique passage 64 to the groove 61 and finally through the hole 62 to the interior of the propeller drive shaft 10. The oil pressure within the drive shaft bears against the piston

head 48 and forces the piston forwardly against the action of spring 54 to the position shown in Figs. 1 and 2.

Because of the spiral grooves on the piston body 49 and the complementary ribs 51 on the sleeve 39, the sleeve will be given a rotary turning movement as the piston moves forwardly. The arms 38 integral with the sleeve 39 also move and since their ends are engaged in the notches 37 in the counterbalance weights 31, 32 (Fig. 2), the latter will be rotated. In this manner the pitch of the blades is thus returned to fine pitch position. Such return pitch changing movement is limited by the stop bolt 58.

Adjustment for proper pitch change may be made when the unit is installed by reason of the slots 47 and also the selection of holes 25 through which the bolts 46 pass.

The embodiment illustrated in Figs. 6 and 7 is quite similar to that illustrated in Figs. 1 to 5, inclusive. In this embodiment the hollow propeller drive shaft 70 supports a propeller hub casting having a central portion 71 surrounding the propeller shaft and which is keyed to rotate therewith. It is secured against longitudinal movement by the rings 72 and 73. The hub casting also has two radially extending tubular portions 74. Threaded within these portions 74 are the inner supporting sleeves 75.

Surrounding the hub casting portions 74 are tubular blade supporting members 76 which support the blades 77 by means of bolts. These supporting members 76 are mounted by the bearings 78, 79 for free rotation about the axis of the hub casting portions 74.

The tubular blade supporting members 76 are each threaded to rings 80, and each carries a segment shaped counterbalance weight 81, 82. The edge portions of the weights are provided with bevel gear portions 83, 84 (see also Fig. 7). The bevel gear portions 83, 84 are engaged respectively by bevel gear sections 85 and 86 on the ends of the arms 87 and 88 carried by or integral with a ring member 89.

The ring member 89 is mounted on a tubular member 90 which is coaxial with the propeller drive shaft 70 and extends forwardly thereof. The outer surface of the tubular member 90 has spiral grooves similar to those illustrated in Figs. 4 and 5 of the first embodiment. The inner surface of the sleeve 89 has ribs which engage in said spiral grooves.

The propeller drive shaft 70, near its front end, is threaded to receive a tubular member 91, the latter having an annular groove 92 engaged by a flange 93 on the ring 73. The end of the propeller shaft 70 is also provided with holes 94, and a locking pin 95 passes outwardly through one of these holes and through a slot 96 in the tubular member 91 to lock the latter to the propeller drive shaft 70.

Threadedly secured within the tubular member 91 is an element 97 having a central bore in which the tubular member 90 is mounted for longitudinal sliding movement. The tubular member 90 forms the body of a piston having a head 98 disposed for sliding movement within the hollow propeller shaft 70 which forms a cylinder for the piston. A coil spring 99 bears against the forward face of the head 98 and at its other end against a shoulder 100 on the element 97.

Surrounding the tubular member 90, forwardly of the sleeve 89 is a collar 101 provided with arms 102, 103 (see Fig. 6) which are secured by the bolts 104 to the element 97. A pin 105 (Figs. 6

and 7) extends through the collar 101 and into a longitudinal slot 106 in the tubular member 90, thus preventing relative turning movement.

It is to be understood that adjustable stops such as those employed in the first embodiment may be employed to limit movement of the arms 81, 88.

The modification of Figs. 6 and 7 operates similarly to that of the first embodiment. When the speed of the propellers increases, a centrifugal force will cause the counterbalance weights 81, 82 to move toward the plane of rotation and the pitch of the blades will be changed to coarse pitch position.

If it is desired to change the pitch to fine pitch, oil under pressure from the aircraft engine (or from an independent source, if desired) is introduced into the hollow propeller shaft 70, forces the piston head 98 forwardly. Because of the spiral groove arrangement between the tubular member 90 and ring 89 the latter will be turned as the tubular member 90 moves forwardly and the bevel gears 85, 86 on the arms 81, 88 will move the counterbalance weights 81, 82 in the opposite direction, thus returning the pitch of the blades to fine pitch position.

Finally, a third modification is illustrated in Fig. 8. This embodiment includes features from each of the other two. In structure and operation it is identical with the embodiment of Figs. 6 and 7 except that the arms 81, 88 instead of having bevel gear portions, are provided with knob ends 108, 109, which are engaged in notches 110, 111 in the peripheral edges of the counterbalance weights 81, 82. In this latter respect the modification is similar to that illustrated in Figs. 1 to 5, inclusive.

In all three embodiments, the oil under pressure for moving the piston forwardly may be supplied through means such as shown in Fig. 1, or alternatively, directly from the engine lubricating system. In this latter case the oil from the engine lubricating system will pass directly from the engine into the hollow propeller drive shaft.

It will be understood that the embodiments illustrated are by way of example and that changes in structure and arrangement may be made within the scope of the invention which is not to be limited except as indicated in the following claims.

We claim:

1. A variable pitch propeller for aircraft and the like comprising, a propeller hub mounted for rotation on a propeller drive shaft, said hub having propeller blade supporting members, propeller blades supported by said members for rotary movement about their longitudinal axes, a segment-shaped counterbalance plate carried by each of said members for rotary movement about said axes, said plates being connected with the propeller blades to turn therewith during pitch changing movement, said plates being disposed in planes parallel to the axis of said propeller drive shaft, a member supported forwardly of said propeller drive shaft for relative rotary movement with respect thereto, said last-mentioned member having arm means provided with a gear portion engaging a gear on a peripheral portion of each of said plates, whereby said plates upon rotation of the hub will move toward the plane of rotation of the blades and effect a pitch change in one direction, and also move said arm means and said last-mentioned member in one direction about the axis of the propeller drive shaft, and hydraulic means for moving said last-mentioned member and arm means in the other direction, whereby said plates are returned to their original

position thus effecting a pitch change to the original pitch position.

2. A variable pitch propeller for aircraft and the like comprising, a propeller hub mounted for rotation on a propeller drive shaft, said hub having propeller blade supporting members, propeller blades supported by said members for rotary movement about their longitudinal axes, a segment-shaped counterbalance plate carried by each of said members for rotary movement about said axes, said plates being connected with the propeller blades to turn therewith during pitch changing movement, said plates being disposed in planes parallel to the axis of said propeller drive shaft, a member supported forwardly of said propeller drive shaft for relative rotary movement with respect thereto, said last-mentioned member having two arms each of which engages a notch in the peripheral portion of said plates, whereby said plates upon rotation of the hub will move toward the plane of rotation of the blades and effect a pitch change in one direction, and also move said arm means and said last-mentioned member in one direction about the axis of the propeller drive shaft, and hydraulic means for moving said last-mentioned member and arm means in the other direction, whereby said plates are returned to their original position thus effecting a pitch change to the original pitch position.

3. A variable pitch propeller for aircraft and the like comprising, a propeller hub mounted for rotation on a hollow propeller drive shaft, said hub having blade supporting members, propeller blades supported by said members for rotary movement about their longitudinal axes, a segment-shaped counterbalance plate carried by each of said members for rotary movement about said axes, said plates being connected with the propeller blades to turn therewith during pitch changing movement, said plates being disposed in planes parallel to the axis of said propeller drive shaft, a member supported forwardly of said propeller drive shaft for relative rotary movement with respect thereto, said last-mentioned member having arm means engaging a peripheral portion of each of said plates, whereby said plates upon rotation of the hub will move toward the plane of rotation of the blades and effect a pitch change in one direction, and also move said arm means and said member in one direction about the axis of the propeller drive shaft, and hydraulic means for moving said last-mentioned member and arm means in the other direction, whereby said plates are returned to their original position thus effecting a pitch change to the original pitch position, said hydraulic means comprising a piston in said hollow tubular drive shaft and a spiral thread connection between said piston and said last-mentioned member, and means for supplying a fluid under pressure to the piston to move it forwardly, whereby relative rotary movement is imparted to said last-mentioned member.

4. A variable pitch propeller for aircraft and the like comprising, a propeller hub mounted for rotation on a propeller drive shaft, said hub having propeller blade receiving members, propeller blades mounted within said members for rotary movement about their longitudinal axes, a segment-shaped counterbalance plate carried by each of said members for rotary movement about said axes, said plate being connected with the propeller blades to turn therewith during pitch changing movement, said plates being disposed in planes parallel to the axis of said propeller drive

shaft, a member supported forwardly of said propeller drive shaft for relative rotary movement with respect thereto, said last-mentioned member having arm means engaging a peripheral portion of each of said plates, whereby said plates upon rotation of the hub will move toward the plane of rotation of the blades and effect a pitch change in one direction, and also move said arm means and said last-mentioned member in one direction about the axis of the propeller drive shaft, and hydraulic means for moving said last-mentioned member and arm means in the other direction, whereby said plates are returned to their original position thus effecting a pitch change to the original pitch position, said last-mentioned member having a hollow hub sleeve portion, a tubular element secured to the front end of the propeller drive shaft and surrounding said hollow hub sleeve portion, a piston mounted for axial movement within the hollow propeller drive shaft, said piston having a forward end portion provided with spiral grooves, the inner surface of said hollow hub sleeve portion having complementary spiral ribs, a cap member secured to said tubular element, said cap member having an inwardly projecting tubular part disposed within the piston body, said piston body being keyed to said tubular part against turning movement, and means for supplying fluid under pressure against said piston to move it forwardly.

5. A variable pitch propeller for aircraft and the like comprising, a propeller hub mounted for rotation on a propeller drive shaft, said hub having propeller blade receiving members, propeller blades mounted within said members for rotary movement about their longitudinal axes, a segment-shaped counterbalance plate carried by each of said members for rotary movement about said axes, said plates being connected with the propeller blades to turn therewith during pitch changing movement, said plates being disposed in planes parallel to the axis of said propeller drive shaft, a member supported forwardly of said propeller drive shaft for relative rotary movement with respect thereto, said last-mentioned member having arm means engaging a peripheral portion of each of said plates, whereby said plates upon rotation of the hub will move toward the plane of rotation of the blades and effect a pitch change in one direction, and also move said arm means and said last-mentioned member in one direction about the axis of the propeller drive shaft, and hydraulic means for moving said last-mentioned member and arm means in the other direction, whereby said plates are returned to their original position thus effecting a pitch change to the original pitch position, said last-mentioned member having a hollow hub sleeve portion, a tubular element secured to the front end of the propeller drive shaft and surrounding said hollow hub sleeve portion, a piston mounted for axial movement within the hollow propeller drive shaft, said piston having a forward end portion provided with spiral grooves, the inner surface of said hollow hub sleeve portion having complementary spiral ribs, a cap member secured to said tubular element, said cap member having an inwardly projecting tubular part disposed within the piston body, said piston body being keyed to said tubular part against turning movement, and means for supplying fluid under pressure against said piston to move it forwardly, and spring means disposed within the piston body and bearing against the cap member for urging the piston rearwardly.

6. A variable pitch propeller for aircraft and the like comprising, a propeller hub mounted for rotation on a propeller drive shaft, said hub having propeller blade receiving members, propeller blades mounted within said members for rotary movement about their longitudinal axes, a segment-shaped counterbalance plate carried by each of said members for rotary movement about said axes, said plates being connected with the propeller blades to turn therewith during pitch changing movement, said plates being disposed in planes parallel to the axis of said propeller drive shaft, a member supported forwardly of said propeller drive shaft for relative rotary movement with respect thereto, said last-mentioned member having arm means engaging a peripheral portion of each of said plates, whereby said plates upon rotation of the hub will move toward the plane of rotation of the blades and effect a pitch change in one direction, and also move said arm means and said last-mentioned member in one direction about the axis of the propeller drive shaft, and hydraulic means for moving said last-mentioned member and arm means in the other direction, whereby said plates are returned to their original position thus effecting a pitch change to the original pitch position, said last-mentioned member having a hollow hub sleeve portion, a tubular element secured to the front end of the propeller drive shaft and surrounding said hollow hub sleeve portion, a piston mounted for axial movement within the hollow propeller drive shaft, said piston having a forward end portion provided with spiral grooves, the inner surface of said hollow hub sleeve portion having complementary spiral ribs, a cap member secured to said tubular element, said cap member having an inwardly projecting tubular part disposed within the piston body, said piston body being keyed to said tubular part against turning movement, means for supplying fluid under pressure against said piston to move it forwardly, and means for adjusting the initial position of said arm means, said adjusting means including a series of holes in a flange integral with said tubular element, and a pair of slotted lugs carried by said cap member whereby the cap member may be bolted to said flange in any one of a number of positions.
